(57) **CLAIM**

The ornamental design for a menstrual cup, as shown and described.

DESCRIPTION

FIG. 1 is a perspective view of a menstrual cup showing our new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom plan view thereof.

The broken lines shown in the drawings are included for the purpose of illustrating portions of the menstrual cup that form no part of the claimed design.
